UNITED STATES PATENT OFFICE.

JOSEPH H. TEMPLIN, OF PHILADELPHIA, PENNSYLVANIA.

SUCTION-CLEANER.

1,079,378.

Specification of Letters Patent. Patented Nov. 25, 1913.

Application filed January 27, 1913. Serial No. 744,617.

To all whom it may concern:

Be it known that I, JOSEPH H. TEMPLIN, a citizen of the United States, residing at Philadelphia, in the county of Philadelphia and State of Pennsylvania, have invented certain new and useful Improvements in Suction-Cleaners, of which the following is a specification.

My invention relates to improvements in suction cleaners, more particularly to that class wherein the suction mechanism combined with the renovating base is moved bodily over the fabric to be cleaned, and wherein the renovating base is provided with two inlet slots arranged parallel with each other and located at the opposite ends of the renovating base.

The object of my invention is to facilitate the reception of articles as matches, shreds of paper, threads and the like into the forward or leading inlet slot of the renovating base. I attain the above object by providing means whereby the suction mechanism and the renovating base with the two inlet slots can be automatically tilted, or means by which either one or the other of the slots can be alternately raised or lowered from or to the floor or fabric to be renovated, that is to say, the forward slot, in the direction 0 which the renovating base is moved, is raised and the rearward slot lowered.

A further object is to provide means for adjustment of the tilting means so that the requisite tilt can be attained suitable for long or short nap, or for hard or soft carpet.

A further object is to provide a brush or means adjacent to the inlet slots to agitate the dust or lint, threads and the like so that the same can be readily lifted by the suction 0 of the air current into the inlet slots.

In the accompanying drawings, in which similar numerals indicate like parts:—Figure 1 is a side view of my device showing both inlet slots resting on the floor. Fig. 2 is a partial side view showing the forward inlet slot tilted off the floor and the rear inlet slot resting on the floor. Fig. 3 is a partial sectional view illustrating the means for adjusting the rollers for operating on light or heavy nap carpets as desired. Fig. 4 is a partial inverted plan view of the roller and brush carrying plate, the rollers and brushes being removed. Fig. 5 is a partial side view showing a modified tilting device. Fig. 6 is a partial end view of Fig. 5.

Referring to the drawings, 1 represents

the motor casing, 2 the fan casing, both combined with the renovator base 3, which is provided with the two parallel inlet slots 4 and 4¹ located at opposite ends of the renovator base; 5 is a screw threaded adjusting plug to which is secured the roller carrying plate 6 by means of clamping screw 7.

8 and 8¹ are the prongs of a fork attached to any well known handle (not shown) by means of which the operator reciprocates the mechanism on the floor. The lower ends of prongs 8—8¹ terminate in hooks 9—9¹ and engage in suitable pockets disposed on either side of the renovator base 3.

10—10¹ are standards formed upon plate 6 and provided with axles 11—11¹ upon which rollers 12—12¹ revolve and sustain the weight of the mechanism, thereby reducing the friction of the renovator base 3 upon the floor.

13—13¹ are projections formed up in plate 6. These projections bear against the side of hooks 9—9¹ of prongs 8—8¹ respectively and steady said plate to prevent the brushes 14—14¹ and the holders 15—15¹ of the same from chafing and binding on the sides of the respective inlets.

When the plug 5 is screwed up as in Fig. 1, the face of the inlet and the roller 12—12¹ as well as the brushes rest on the floor, or fabric to be renovated. When however plug 5 is partially unscrewed, the face of the rollers 12—12¹ is lower than the inlet face or the brushes and therefore but one inlet rests on the floor, the other being tilted upward to a greater or less degree in proportion to the amount of adjustment, said adjustment being made to suit the conditions or fabric to be renovated.

The pivotal point of the hooks 9—9¹ is lower, as shown, than the pivotal point of the rollers 12—12¹ and the resultant effect of the operator pushing on the handle to move the apparatus, is to raise the forward slot from the floor as the friction of moving the apparatus bodily is greater than the force required to tilt the mechanism, and vice versa, the effect is the same when the operator draws the apparatus instead of pushing, the forward or leading inlet slot in the direction of travel of the apparatus is always raised. The brushes 14—14¹ however are very slightly affected by the tilting operation as the plate 6 is elastic. No undue pressure is put on the brushes and they remain in contact with the floor at all times.

agitating and loosening the dust or particles that tend to adhere to the fabric, thereby facilitating the removal of the same so that the renovating is accomplished thoroughly and efficiently.

In Figs. 5 and 6, I have illustrated a modified form of my tilting device performing the same function but not adjustable as to the degree of tilt, but set at the tilt as required in the average household. In the modified form the roller 12 revolves on pin or axle 11, secured to lever or link 16 pivoted on pin 17 which supports and balances the suction mechanism combined with the renovator base 3. Prong 8 of the handle-fork hooks into the eye 18 of lever or link 16, and at this point, power is applied for reciprocating the suction mechanism over the floor. When the handle is pushed, hook 9 pushes link 16 forward thereby changing the position of roller 12 forward of the center of gravity causing the forward inlet slot to raise off the floor and the rear inlet slot to rest upon the floor and vice versa when the suction cleaner is drawn instead of pushed over the floor.

From the foregoing, the operation of the device can be readily understood.

While I have illustrated and described my preferable design to accomplish my purpose, I do not wish to be confined to the exact construction of the same in all its details, as changes may be made by those skilled in the art, that would come within the scope of my invention.

What I therefore claim and for which I desire Letters Patent is:

1. In a suction cleaner, a hollow base provided with parallel inlet slots, a suction pump mounted upon and communicating with said base, a motor for operating said pump, a pivotal support between said slots, and means for reciprocating the cleaner on the floor and tilting it upon said support.
2. In a suction cleaner, a hollow base provided with parallel inlet slots, a suction pump mounted upon and communicating

with said base, a motor for operating said pump, a pivotal support between said slots, means for adjusting the height of said pivotal support, and means for reciprocating the cleaner over the floor and tilting it upon said support.

3. In a suction cleaner, a hollow base provided with parallel inlet slots, a suction pump mounted upon and communicating with said base, a motor for operating said pump, a pivotal support between said slots, means for detachably clamping said support to said base, means for adjusting the height of said support, and means for reciprocating the cleaner over the floor and tilting it upon said support.

4. In a suction cleaner, a hollow base having a suction inlet, a plate provided with clamping means for detachably clamping the same to said base, projections formed on said plate to prevent said plate from turning, a pair of standards formed on said plate, said standards provided with axles and a roller revolvably retained on each axle.

5. In a suction cleaner, a hollow base having a suction inlet, a plate provided with means for detachably clamping the same to said base, said plate provided with a brush adjacent to said suction inlet, a pair of standards formed on said plate, each of said standards provided with an axle, and a roller revolvably retained on said axles.

6. In a suction cleaner, a hollow base provided with parallel inlet slots, a plate provided with means for detachably clamping the same to said base between said slots, said plate provided with a brush adjacent to each of said inlet slots, a pair of standards formed on said plate, each of said standards provided with an axle, and a roller revolvably retained on each axle.

In testimony whereof I affix my signature in presence of two witnesses.

JOSEPH H. TEMPLIN.
